Primary Examiner — Patricia Palasik*(74) Attorney, Agent, or Firm* — Studebaker & Brackett PC(57) **CLAIM**

The ornamental design for an oil funnel, as shown and described.

DESCRIPTION

FIG. 1 is a perspective view showing our new design for an oil funnel,
 FIG. 2 is another perspective view thereof,
 FIG. 3 is a top view thereof,
 FIG. 4 is a bottom view thereof,
 FIG. 5 is a right side view thereof,
 FIG. 6 is a left side view thereof,
 FIG. 7 is a front view thereof,
 FIG. 8 is a rear view thereof,
 FIG. 9 is a perspective view of an alternate embodiment of the oil funnel in FIGS. 1 through 8,
 FIG. 10 is another perspective view thereof,
 FIG. 11 is a top view thereof,
 FIG. 12 is a bottom view thereof,
 FIG. 13 is a right side view thereof,
 FIG. 14 is a left side view thereof,
 FIG. 15 is a front view thereof, and,
 FIG. 16 is a rear view thereof.
